UNITED STATES PATENT OFFICE.

WILLIAM H. GOLDING, OF CHELSEA, MASSACHUSETTS.

COMBINED SIDE AND END LOCK FOR GALLEYS.

SPECIFICATION forming part of Letters Patent No. 320,128, dated June 16, 1885.

Application filed May 5, 1884. (No model.)

To all whom it may concern:

Be it known that I, WILLIAM H. GOLDING, a citizen of the United States, residing at Chelsea, in the county of Suffolk and State 5 of Massachusetts, have invented certain new and useful Improvements in Combined Side and End Locks for Galleys, of which the following is a specification, reference being had therein to the accompanying drawings, in 10 which—

Figure 1 is a plan of a galley and furniture comprising my improved end lock. Fig. 2 is a section on line $x x$ of Fig. 1, and Fig. 3 is a bottom view of my improved end lock detached.

Like letters refer to like parts in all the figures.

A represents a galley of any usual construction, in which is a column or body of type, B, 20 a side-stick, C, and ordinary quoins, D.

E represents my improved end lock, which comprises a quoin-shaped body, e , slotted, as at e' , from its lower surface upward, the upper wall of the slot being formed by a bridge 25 or connecting portion, e'' . From the wall of the slot opposite the body portion projects a bar or end piece, e^3 , the inner face of which is exactly at a right angle to the walls of the slot e' , and the bottom of which lies in the

30 same plane as that of the body portion, so that when placed in a galley the end of the column against which the end piece is placed will be squarely held, while the side-stick will pass through the slot and rest upon the bottom

35 of the galley, when by means of the quoin-shaped body portion and any usual quoin the

end piece may be locked at any desired point within the galley.

By the use of my improved end lock I avoid the necessity of all supplementary securing 40 devices which have hitherto been attached to side-stick-embracing end locks, and provide an article complete in itself, strong, and serviceable, and adapted by the relative arrangement of its parts to perform accurately the 45 functions for which it is designed, and by making the lateral extension somewhat shorter than the width of ordinary columns it is adapted to permit the body portion to perform its function of a side lock.

Having described my invention and its 50 operation, what I claim as new is—

1. A combined side and end lock, the body portion of which has the inclined form of an ordinary quoin, substantially as specified.

2. The combined side and end lock, consisting of the body portion e , having an outer inclined side and a laterally-projecting end piece, connected to the body by a bridge, substantially as specified.

3. The combination of the galley A, side-stick C, quoin D, and the end and side lock, E, having the slotted body e , provided with an outer inclined side, substantially as shown and described.

In testimony whereof I affix my signature in presence of two witnesses.

WILLIAM H. GOLDING.
